UNITED STATES PATENT OFFICE.

JOSEPH RENÉ AYOTTE, OF CHICAGO, ILLINOIS.

HAND-TOOL.

1,395,887.

Specification of Letters Patent.

Patented Nov. 1, 1921.

Application filed October 31, 1919. Serial No. 334,715.

To all whom it may concern:

Be it known that I, JOSEPH RENÉ AYOTTE, a subject of the King of Great Britain, residing at Chicago, in the county of Cook and 5 State of Illinois, have invented certain new and useful Improvements in Hand-Tools, of which the following is a specification.

This invention relates to certain improvements in hand tools, such as wrenches and 10 the like. It has been my aim in the development of the invention to devise a tool of the kind described which may be easily operated and applied to parts that are located in relatively inaccessible places; to construct the 15 tool so that it may be readily adjusted to operate most effectively under different conditions; to provide means for securing to the tool parts which are formed specially to cooperate with other parts that are to be acted 20 upon; and generally to so arrange and combine its component elements in a manner that will produce a strong, durable and adjustable implement. The invention resides further in numerous other features of construction and combinations of parts, all of 25 which will more clearly hereinafter appear in the specification to follow wherein reference is made to the accompanying drawings which exhibit an exemplification of this invention in the manner following:

Figure 1 shows in side elevation the tool with its operating handle slightly extended therefrom.

Fig. 2 is a longitudinal section through 35 the tool showing its handle parts closed up or collapsed;

Fig. 3 is a detail, partly in section, showing the socket member attached to the tool end;

Fig. 4 is a transverse section taken on line 4-4 of Fig. 3;

Fig. 5 is a transverse section taken on line 5-5 of Fig. 2;

Figs. 6 and 7 are transverse sections taken 45 on line 6-6 of Fig. 1, the former looking in the direction of the arrows, and the latter reversely thereto;

Figs. 8 and 9 are transverse sections taken 50 respectively on lines 8-8 and 9-9 of Fig. 2;

Fig. 10 is a detail, partly in section, showing a modified construction of the upper end of the intermediate sleeve;

Fig. 11 is a transverse section taken on the line 11-11 of Fig. 10;

Fig. 12 is a fragmentary view in elevation 55 suggesting an alternative form of external configuration for the extensible tube; and

Fig. 13 is a sectional detail of the upper end of a modified operating handle.

Referring particularly to Fig. 2, it will be 60 noted that the principal parts of the present tool consist of an outer shell or casing A, which surrounds a sleeve B within which is an extensible tube C. At its lower end the sleeve is connected as by means of a universal joint 15 with a thimble D having an enlarged head 16 which presents a shoulder 17 in abutting relation to the lower end of the casing which, it will be noted, may be bent 65 at an angle relative to the main portion of 70 the tool. Any suitable opening 14 may be formed in the casing near the joint 15, as shown, to facilitate assembly and lubrication of the parts inside. At its upper end the sleeve is formed with a head 18 which over- 75 lies a washer 19 that abuts the upper end of the casing. By these means the sleeve and thimble are maintained in a fixed longitudinal position within the casing.

Through the medium of the sleeve rotary 80 motion may be communicated to the thimble which, as will be noted best in Fig. 3, is operatively seated against a plurality of balls 20 that, in the construction shown, are socketed in the walls of the casing. The thimble 85 is furthermore adapted to receive a tool or socket member E that is adapted to engage with the work, and for this purpose may be formed interiorly with polygonal faces and with a recess 21 within which is located a 90 leaf spring 22 secured in place as by means of a pin 23. The socket member, which cooperates with the thimble thus formed, is shown to be provided with suitably polygonal faces 24 to fit non-rotatably within 95 the thimble, and is further provided with an annular groove 25 to receive the hooked end 26 of the leaf spring. According to this construction, the socket member may be slipped in and out of the thimble against 100 the tension of the leaf spring whose normal tendency is to hold the socket member operatively in position.

In the operation of the tool, the casing A, which functions as a stationary handle, is 105 held against rotation, its gripping portion being preferably milled or knurled as shown at 27. Rotation of the sleeve B is effectu-

ated through the medium of the tube C, which is non-rotatably connected therewith as by means of a pin 28 that is extended through the tube with one end 29 thereof projected exteriorly to lie within a slot 30 5 that is formed longitudinally of the sleeve. According to this construction, the tube and sleeve are locked in a relatively non-rotatable relation, the tube being free, however, to 10 move longitudinally of the tool as required for purposes of adjustment. To lock the tube in a fixed longitudinal position, I have shown a thumb set screw 31 that is threaded into the sleeve head 18 in a manner to prevent 15 its acting end against the tube which may conveniently be provided at intervals with notches 32 with any one of which the set screw may coöperate. Such a notched construction, however, may be modified, if 20 desired, as, for instance, by employing a knurled or milled surface, such as is suggested in Fig. 12.

The upper end of the tube terminates in a clutch head F which overlies the sleeve head, and which is preferably formed with 25 radially disposed slots 33, the number of which, as appears in Fig. 6, may conveniently be four. Arranged in clutching relation to coöperate with these slots are oppositely disposed lugs 34, depending from the lower end of the tool head G which abuts the clutch head, and which is movably connected therewith through the medium of a 30 fixed tube 35 having its lower end apertured to receive a locking pin 36 which extends through the clutch head as well; the upper end of this tube 35 extends within an axial bore of the tool head whose walls are formed 35 interiorly with threads 37 projecting therein to coöperate with a threaded plug 38 adapted to be screwed into place against a shoulder 39 below which is a chamber containing a spring 40 which is coiled around the tube 35 presenting one of its ends against a shoulder 41, and its other against a washer 42 which underlies a pin 43 that passes through the walls of the tube in normal alinement with diametrically opposed openings 44 that are formed in the walls of the tool head. 45 According to the construction described, the tool head may be moved longitudinally of the tube 35 against the tension of the spring 40 to disengage the lugs 34 from the slots 33 that are formed in the clutch head so as 50 to permit the tool head to be rotated without communicating its motion to the remaining parts of the implement.

To facilitate operation of the tool, I have provided a handle pin 45 that is adapted for 60 insertion through opposite openings 46 adjacent the upper end of the tool head. This handle pin may be of any desired length, and be adjusted lengthwise in the tool head in any selected position. In the accomplishment 65 of this result, I make use of a friction

button that is mounted in the plug 38 whose body is hollow to receive a coiled spring 47 which acts against a cup-shaped button 48 that is slidably arranged within the plug chamber. As appears clearly in Fig. 2, the 70 acting end of this button is rounded to project slightly beyond the upper face of the plug where lips 49 may be provided to overlie the edges of the button to confine it in place, but not to interfere with its frictional 75 engagement with the handle pin. By the means described a sufficient pressure is at all times exerted against the pin to prevent its free sliding movement crosswise of the tool head.

It has already been explained that the tool may be extended longitudinally and, when used, one hand will grip the casing while the other will grasp the handle pin to effect 85 a rotation of the thimble and socket member 90 therein so as to properly coöperate with the work. After imparting to the handle pin a quarter turn, the tool head may be retracted against the tension of the spring 40 to unclutch the lugs 34 from the slots 33 preparatory to reclutching the parts in a different angular relation. It is accordingly unnecessary to shift the position of either hand upon the parts that are grasped.

In Figs. 10 and 11, there is shown a modified connection between the sleeve B and extensible tube C. In this construction, it will be noted that I have provided a cross pin 50 which extends through the tube C to project both of its ends within slots 51 100 which are formed longitudinally in the inner walls of the sleeve B so as to lock these parts in a non-rotatable relation to each other. It is preferred that the upper end of the sleeve be provided with a separable head 105 52 which may be threaded upon the sleeve as shown. In all other respects the construction suggested in these figures may be the same as that elsewhere described.

Referring now to Fig. 13, I have shown a modified construction of tool head wherein the tube C and the head G may be integrally formed. The walls of this head are suitably apertured to receive a handle pin 55 which is acted upon by a button 56 that is 110 influenced by a spring 57 suitably socketed within a plug 58 that is threaded within the head in a manner similar to that already explained. While this construction does not provide for clutching and unclutching the 115 tool head relative to the tube, it nevertheless embodies several of the improved features 120 of this invention.

The implement that has been herein described may be constructed to any desired 125 proportions and of any suitable materials. Changes or modifications may, of course, be made without sacrificing the advantages of this invention, and in respect of all such constructions, in so far as they are defined in 130

the following claims, I desire that they should be included within the scope of this patent.

I claim:

- 5 1. In a tool of the kind described, the combination of a bent casing within which is located at one end a tool member, and driving means within the tube for imparting rotation to the member, including a sleeve 10 having a universal and non-rotatable connection therewith, a tube non-rotatably connected with the sleeve, two heads in end to end relation arranged at the sleeve end, one fixed and the other rotatable relative thereto, clutch elements carried by said heads in coöperating relation such that both heads may be rotated in unison in either direction, tension means for normally maintaining said heads in clutching relation, a handle pin 15 slidably arranged crosswise of the one head and freely adjustable thereon, and a friction button arranged within the same head in coöperating relation to the handle pin for maintaining the same in any desired position of longitudinal adjustment, substantially as described.
2. In a tool of the kind described, the combination of a casing, a sleeve therewithin, a tool head mounted in the casing and adapted to be turned with movement of the sleeve, a pair of heads connected with the sleeve, one fast and the other loose relative thereto, and a connection between said heads comprising slots on the one and lugs on the other arranged in coöperative clutching relation, and means for normally holding the two heads in clutching relation comprising a tube locked to the one and extended with- 20 25 30 35
- in the other whose body is interiorly formed to provide a chamber surrounding the tube, 40 a spring within the chamber coiled around the tube and exerting pressure endwise against the walls at one end of the chamber, and means carried by the tube against which the other end of the spring exerts pressure 45 to thereby hold the rotatable head in clutching relation with the stationary handle, substantially as described.
3. In a tool of the kind described, the combination of a casing having a bend near one end thereof, a headed sleeve within one end of the casing and a headed thimble within the other, the headed portions of the sleeve and thimble overlying the proximate ends of the casing, a universal joint connecting the sleeve and thimble, means for rotating the sleeve and extensible relative thereto, comprising a tube arranged within the sleeve and having a pin projected therefrom to lie within a slot that is formed longitudinally of the sleeve, means carried by the sleeve head adjustable toward and from the tube to lock the tube in any selected position of extension relative to the sleeve, and a handle associated with the tool for imparting rotary motion to the tube, said handle including a pin arranged transversely to the axis of the tool and movable crosswise thereof in the direction of its own axis, and a friction device carried by the tool in association with the pin to maintain the same in any given position of adjustment, substantially as described.
